 a corporation of Massachusetts

Application November 10, 1944, Serial No. 562,809

19 Claims. (Cl. 66—50)

1

This invention relates to racking means for a trick wheel or other cyclically operating mechanism of a knitting machine.

Knitting machines are commonly provided with trick wheels which carry in axially extending slots jacks containing butts arranged in predetermined fashions to control the production of patterns. Such trick wheels are required to pass through successive cycles to form repetitions of the controlled pattern and are subject to special controlling actions. For example, in the usual operation the trick wheel is advanced one step in each course of knitting to present a different array of butts to the controlled elements. This action generally occurs constantly during the knitting of the leg of a stocking. When the knitting of a heel begins the instep needles in the machine are thrown out of action, to be later restored to action during the knitting of the foot. Ordinarily the pattern running along the leg should be continued without interruption through the instep of the stocking. Consequently, the trick wheel should not advance during the knitting of the heel. During the formation of the foot the advance of the trick wheel should be the same as during the knitting of the leg.

Again, when the toe is reached, it is generally desirable to stop the advance of the trick wheel while the machine effects reciprocatory knitting. At the end of such reciprocatory knitting no further controlling actions by the trick wheel are generally desired until the beginning of the knitting of the leg of the next stocking. Ordinarily, when the trick wheel advance is stopped at the beginning of the knitting of the toe it will not be in the desired position for the resumption of control during the knitting of the leg of the next stocking. Consequently, it is necessary that the trick wheel be timed up and then come to rest in a definite position to secure a proper pattern controlling action in the next stocking. This is generally accomplished by causing the trick wheel to be advanced during the knitting of the loopers rounds or waste courses of the stocking.

It will be evident that for the formation of the most elaborate patterns which are required, the trick wheel should contain a maximum number of jacks. Since this number is fixed by the slots in the trick wheel, it will be evident that a serious limitation on the extent of the pattern would be imposed if the number of courses involved in a repeat of the pattern had to be equal to the number of slots in the trick wheel or some submultiple thereof. To secure patterns having repeats of different numbers of courses, it is de-

2

sirable to have provision made for single or double advances of the trick wheel, desirably under the control of the trick wheel itself, so that it will complete a cycle during the desired number of courses.

The above motions and controls of a trick wheel are known in the art.

Ordinarily, trick wheels of the type indicated are advanced by conventional ratchet and pawl mechanisms. The disadvantage of the use of such mechanisms is that coupled with the rapidity of movement which is required is a tendency toward overrunning which if it occurs will obviously destroy the intended pattern in the stocking. To prevent overrunning friction is generally applied to the pattern drum or trick wheel which is being racked and this in turn imposes a resistance to movement of the racking mechanism which, if racking is effected by means connected to the cylinder of the machine, will set up objectionable vibration. This may be eliminated if, by prevention of overrun, the necessity of putting friction on the drum is eliminated.

Furthermore, any tendency towards overrun requires a corresponding greater distance between steps of the drum. If overrun can be prevented, the angular range of each step may be reduced, with consequent narrowing of the lap of the pattern where change occurs and the possibility of providing for more drum moves with a drum of given diameter.

One object of the present invention is the provision of a racking mechanism for a knitting machine which is positive in its action in prevention of overrunning movements and thus makes possible attaining of the advantages just noted. A further object of the invention is the provision of a racking mechanism of this type which is capable of controlled action to secure the necessary stopping of a rotary member, the timing thereof, and single or double advances thereof, as indicated above.

These and other objects of the invention relating particularly to details will become apparent from the following description read in conjunction with the accompanying drawings in which:

Figure 1 is a fragmentary plan view, partly diagrammatic illustrating the application of the invention to drive of a trick wheel of a knitting machine;

Figure 2 is a fragmentary illustration showing the means for effecting control from the main cam drum of the machine;

Figure 3 is a plan view, partly in section, simi-

lar to Figure 1 but showing certain parts above those illustrated in Figure 1; and

Figure 4 is an elevation looking at the right hand side of Figure 1 and the lower side of Figure 3.

Referring first to Figure 1, the location of the rotary needle cylinder of a knitting machine is indicated at 2. Rotating with this, for example, by reason of its being secured to the cylinder gear, is a cam 4 which during rotary knitting moves in the direction indicated by the arrows 6. A bell crank 8 having a fixed pivot at 10 is arranged to be acted upon by the cam 4 to cause its end 12 to engage and move the adjustable screw 14 carried by the lever 16 having a fixed pivot at 18. A spring 19 urges the lever 16 in a clockwise direction to maintain its screw 14 in contact with bell crank 8 up to a limiting position defined by contact of a stop screw 22 with a fixed pin indicated at 20.

Pivoted at 24 to the lever 16 is a gear segment 26 provided with teeth at 28. An adjustable eccentric stop pin 30 is arranged behind the segment 26 as indicated to limit clockwise movement of the segment with respect to the fixed parts of the machine. An adjustable screw 32 carried by the segment is arranged to engage a lug 34 on the arm 16 to limit clockwise movement of the segment relative to the arm about the pivot 24.

A gear 36 mounted to rotate about a center 37 carries the trick wheel 38, which may be of the conventional type commonly provided in knitting machines and consisting of a slotted cylinder in which jacks 39 may be located having butts 41 arranged at various levels and in various arrangements at said levels.

The bell crank 8 carries a lug 40 upstanding therefrom which has a range of movement, upon oscillation of the bell crank 8, between the position shown in full lines at 40 and the position shown in dotted lines at 40'. A lever 43 pivoted upon a fixed post 48 is provided with an opening 41 which has a series of steps 42, 44 and 46 which in various phases of the operation are adapted to be engaged by the lug 40. A spring 50 urges the lever 43 in a counterclockwise direction against the pull which is produced through a Bowden wire and a spring 60 which is of sufficient strength to overcome the spring 50. As indicated in Figure 2, the opposite end of the Bowden wire is secured to an arm 62 extending from a push rod 64 which is adapted to be raised by the action of cams on a lever 66. The cams which act upon the lever 66 are carried by the main cam drum of the machine and may comprise, for the knitting of a conventional stocking, a cam 70 which acts upon the follower lever 66 during the knitting of a leg, a cam 72 which acts upon the lever during the knitting of a heel, cam 74 which is active during the knitting of the foot, cam 76 active during toe knitting and the space 78 which may be provided by the face of the drum and which is effective during knitting of the loopers rounds to effect timing.

Referring to Figure 3, there is indicated therein a second lever 80 which is also pivoted upon the post 48 above the lever 43. This lever is provided with a step 82 which, as will be evident from the figures, is adapted to move in the same path as the step 42 in cooperating with the lug 40. A spring 84 urges the lever 80 in a counterclockwise direction to bring an adjustable stop screw 86 carried by the lever into engagement with the downturned end 88 of a slide 90 mount-

ed for horizontal movement in suitable guides in the machine frame.

The slide 90 is provided with a follower portion 92, which is arranged to be engaged by butts which are located in a particular level, for example, the lowermost level 94, of butts in the trick wheel.

During the knitting of a leg of a stocking, the cam 70 on the main cam drum effects the location of the lever 43 in the position illustrated in Figure 1.

The space between the steps 42 and 46 is located in the path of the lug 40 so that this lug has a full range of movement without interference by the lever 43 when the bell crank 8 is swung and released by the cam 4 during each rotation of the needle cylinder corresponding to the formation of each course of the leg. Disregarding for the moment the action of the lever 80, the effect of the foregoing is to advance the trick wheel 38 through a double step upon each revolution of the needle cylinder, such double steps corresponding to the angular spacing of two teeth of the gear 36 and to the angular spacing of two jacks in the trick wheel. Starting from the position illustrated in Figure 1 this is effected in the following manner: The pivot 24 is arranged to involve a substantial degree of friction. When the lever 16 occupies its extreme clockwise position as illustrated due to the extreme counterclockwise position of bell crank 8, the segment 26 will have been positioned by engagement with the stop 30. As the bell crank 8 rides upwardly on the cam 4, the lever 16 is rocked counterclockwise and during such rocking movement, due to the friction action mentioned, the angular relationship between the segment 26 and lever 16 is maintained with the result that a predetermined meshing of the segment 28 and the gear 36 takes place. Following a completion of meshing, the continued counterclockwise movement of the levers 16 will cause a widening of the angle between the segment 26 and the lever 16 resulting in there being imparted to the gear 36 a movement equivalent to the angular spacing of two teeth of the gear. The limit of this movement occurs when the screw 32 engages the lug 34 which should coincide substantially with the bell crank 8 reaching the top of the cam 4. Actually, the arresting action may occur just slightly prior to this, the resilience of the parts permitting the cam 4 to pass the bell crank 8.

As the bell crank is released by the cam, the lever 16 moves clockwise under the action of the spring 19, to a position limited by engagement of the screw 22 with the stop pin 20. At the beginning of this movement the segment 26 moves, due to the friction at the pivot 24, as an integral part of the lever 16, out of mesh with gear 36 until it engages the stop 30 whereupon it is arrested, and further movement of the lever 16 to its final position results in decrease of the angle between the segment and the lever. The parts are thus returned to the original position first described preparatory to the next action by the cam 4 which results in meshing of the segment with the gear. In moving outwardly the segment so moves that its teeth leave those of gear 36 without tendency to impart either backward or forward movement to the gear.

This result is attained by such relative arrangement of the parts that movement occurs substantially along a line joining the center of gear 36 with the center of curvature of the segment. The above action occurs so long as a butt 94

engages the slide 90 to maintain the shoulder 82 of lever 80 out of the path of the lug 40. In the absence of a butt 94 acting on the slide 90, the step 82 will be in the path of lug 40, and consequently, when the bell crank is released by the cam 4 its counterclockwise movement is limited to the end that the lever 16 is arrested short of its extreme clockwise position i. e., the screw 22 is, in its final position, spaced from the stop pin 20. Under these conditions the angle between the segment 26 and the lever 16 will be greater than before so that when the lever 16 next moves counterclockwise, due to the action of cam 4, meshing will not occur two teeth behind the previous point of meshing but only one tooth behind that point. As a consequence, there will be imparted to the gear 36 an angular movement through the spacing of only a single tooth, or in other words, the trick wheel will have imparted thereto a single step.

The result of the above is that, by reason of a predetermined arrangement of butts 94, a particular succession of single and double steps may be imparted to the trick wheel to result in its complete rotation during the occurrence of various numbers of courses of knitting, with the result that within wide limits the cycle of repetition of the pattern may be varied. It will be noted that in either case it is impossible for the gear 36 to overrun the movement imparted to it by the segment 26, since at the end of the advancing movement, the segment and the gear are in mesh and the gear is definitely brought to rest before release of the gear by the segment can occur. The gear 36 cannot possibly force the segment 26 out of mesh since the segment is effectively rigid with the lever 16 at the end of the racking movement by reason of engagement of screw 32 with the lug 34.

In order to arrest the motion of the trick wheel during the knitting of the heel, the cam 72 produces a pull on the Bowden wire to urge the lever 43 in a clockwise direction under the action of the spring 60. The timing is such that the rise of the follower lever 66 on the cam 72 occurs when the bell crank 8 is not being acted upon by the cam 4. As a consequence, the side of the step 46 first engages the lug 40, the spring 60 yielding when such engagement occurs. As soon as the bell crank 8 rides up the cam 4 so that the lug 40 clears the step 46, the step will then be snapped behind the lug so that counterclockwise movement of the bell crank 8 is prevented even though it is released by the cam 4. As a result, during the formation of the heel, the segment 26 is held in mesh with the gear 36 retaining the trick wheel in fixed position despite continued movement of the needle cylinder, which during formation of the heel, will be reciprocatory.

When circular knitting is resumed through the foot, the follower 66 drops off cam 72 upon the cam 74 resulting in return of the lever 43 to the identical position which it occupied during the knitting of the leg. Normal advances of the trick wheel through single or double steps may then take place to continue the pattern through the foot.

When the knitting of the toe is reached, the cam 76 acts identically as would the cam 72 during the heel formation. Accordingly, the advance of the trick wheel is again arrested, the trick wheel being locked in position by the segment.

Following the knitting of the toe and beginning of the knitting of the loopers rounds, the lever 66 drops upon the drum face at 78. This drop

would be sufficient to permit the step 44 to be brought into the path of the lug 40. However, movement of the lever 43 does not occur to this extent inasmuch as the pin 52 carried by it will drop to the position 52' into engagement with the circular edge of the cam disc 54. When this occurs the step 42 is brought into the path of the lug 40.

As previously pointed out, the step 42 bears the same relationship to the lug 40 as the step 82 of the lever 80, preventing the bell crank 8 from moving to its normal counterclockwise position and thus limiting the extent to which the lever 16 may move clockwise. As a consequence, irrespective of the butt arrangement at 94 on the trick wheel, and irrespective of the position of the lever 80 which may be moved by the action of such butts, the movements of the parts are such that only single steps of the trick wheel may occur. Such single steps are for the purpose of advancing the trick wheel toward its initial position for the beginning of the pattern in the leg of the next stocking. It may be noted that cam 76 may be omitted, in which case this retiming phase of the operation may begin simultaneously with the beginning of knitting of the toe.

The single step advances continue until the notch 56 reaches the position 52' of the pin 52. As soon as the pin 52 is free to drop into the notch, the spring 50 moves the lever 43 further in a counterclockwise direction to bring the step 44 into the path of the lug 40 as soon as the bell crank 8 is moved clockwise after the pin drops into the notch. The step 44 then occupies the same position as the step 46 occupied during heel and toe knitting, with the result that the racking is completely interrupted, the trick wheel being locked in position by the segment 26, in preparation for properly timed control in the knitting of the next stocking.

This locked condition continues until the follower 66 rises on the cam 70, whereupon the lever 43 is again moved clockwise to clear both steps 44 and 42 from the path of the lug 40 so that the racking operations may be resumed.

It may be noted that, if desired, by a proper shaping of cam 4 the lever 8 may be rocked to effect advance of the trick wheel during both forward and reverse strokes of the needle cylinder during reciprocation. In this fashion patterning may be accomplished, for example, during the knitting of split work.

What I claim and desire to protect by Letters Patent is:

1. In a knitting machine, rotary means including a toothed member, a first lever, means for imparting oscillatory motions to said lever, a second lever having at least one tooth engageable with teeth of the toothed member, the second lever being pivoted to the first lever but being restrained from free angular movement relative thereto, a stop engageable by the second lever to limit movement thereof away from the toothed member, and stop means for limiting angular movement of the second lever relative to the first in one direction, so that during an oscillation of the first lever in one direction the second lever first moves therewith to cause its tooth to mesh with said toothed member and then moves angularly relatively thereto to a position limited by said stop means to impart an advancing movement to said toothed member, and so that during an oscillation of the first lever in the reverse direction the second lever first moves therewith to disengage the tooth from the toothed member

and then engages said stop to be retarded thereby to establish a definite angular relationship between the levers at the end of the movement of the first lever.

2. In a knitting machine, rotary means including a toothed member, a first lever, means for imparting oscillatory motions to said lever, a second lever having at least one tooth engageable with teeth of the toothed member, the second lever being pivoted to the first lever but being frictionally restrained from free angular movement relative thereto, a stop engageable by the second lever to limit movement thereof away from the toothed member, and stop means for limiting angular movement of the second lever relative to the first in one direction, so that during an oscillation of the first lever in one direction the second lever first moves therewith to cause its tooth to mesh with said toothed member and then moves angularly relatively thereto to a position limited by said stop means to impart an advancing movement to said toothed member, and so that during an oscillation of the first lever in the reverse direction the second lever first moves therewith to disengage the tooth from the toothed member and then engages said stop to be retarded thereby to establish a definite angular relationship between the levers at the end of the movement of the first lever.

3. In a knitting machine, rotary means including a toothed member, an oscillating element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, and stop means for limiting angular movement of the lever relative to the element in one direction, so that during an oscillation of the element in one direction the lever first moves therewith to cause its tooth to mesh with said toothed member and then moves angularly relatively thereto to a position limited by said stop means to impart an advancing movement to said toothed member, and so that during an oscillation of the element in the reverse direction the lever first moves therewith to disengage the tooth from the toothed member and then engages said stop to be retarded thereby to establish a definite angular relationship between the lever and element at the end of movement of the element.

4. In a knitting machine, rotary means including a toothed member, an oscillating element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, stop means for limiting angular movement of the lever relative to the element in one direction, so that during an oscillation of the element in one direction the lever first moves therewith to cause its tooth to mesh with said toothed member and then moves angularly relatively thereto to a position limited by said stop means to impart an advancing movement to said toothed member, and so that during an oscillation of the element in the reverse direction the lever first moves therewith to disengage the tooth from the toothed member and then engages said stop to be retarded thereby to establish a definite angular relationship be-

tween the lever and element at the end of movement of the element, and means for varying the extent of oscillation of the element to control the advance of the toothed member.

5. In a knitting machine, rotary means including a toothed member, an oscillating element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, stop means for limiting angular movement of the lever relative to the element in one direction, so that during an oscillation of the element in one direction the lever first moves therewith to cause its tooth to mesh with said toothed member and then moves angularly relatively thereto to a position limited by said stop means to impart an advancing movement to said toothed member, and so that during an oscillation of the element in the reverse direction the lever first moves therewith to disengage the tooth from the toothed member and then engages said stop to be retarded thereby to establish a definite angular relationship between the lever and element at the end of movement of the element, means for varying the extent of oscillation of the element to control the advance of the toothed member.

10 20 25 30 35 40 45 50 55 60 65 70

6. In a knitting machine, rotary means including a toothed member, an oscillating element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, stop means for limiting angular movement of the lever relative to the element in one direction, so that during an oscillation of the element in one direction the lever first moves therewith to cause its tooth to mesh with said toothed member and then moves angularly relatively thereto to a position limited by said stop means to impart an advancing movement to said toothed member, and so that during an oscillation of the element in the reverse direction the lever first moves therewith to disengage the tooth from the toothed member and then engages said stop to be retarded thereby to establish a definite angular relationship between the lever and element at the end of movement of the element, and means rotating with the toothed member for controlling the last named means.

7. In a knitting machine, rotary means including a toothed member, an oscillatory element, means for imparting oscillatory motions to said element, a lever having at least one tooth engageable with teeth of the toothed member, the lever being pivoted to said element but being restrained from free angular movement relative thereto and a stop engageable by the lever to limit movement thereof away from the toothed member, so that during an oscillation of the element in one direction the lever first moves therewith to cause its tooth to mesh with said toothed member and then moves angularly relatively thereto to impart an advancing movement to said toothed member, and so that during an oscillation of the element in the reverse direction the lever first moves therewith to cause its tooth to mesh with said toothed member and then moves angularly relatively thereto to impart an advancing movement to said toothed member, and so that during an oscillation of the element in the reverse direction the lever

75

first moves therewith to disengage the tooth from the toothed member and then engages said stop to be retarded thereby to establish a definite angular relationship between the lever and element at the end of movement of the element.

8. In a knitting machine, rotary means including a toothed member, an oscillatory element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, so that during an oscillation of the element in one direction the lever first moves therewith to cause its tooth to mesh with said toothed member and then moves angularly relatively thereto to impart an advancing movement to said toothed member, and so that during an oscillation of the element in the reverse direction the lever first moves therewith to disengage the tooth from the toothed member and then engages said stop to be retarded thereby to establish a definite angular relationship between the lever and element at the end of movement of the element, and means for varying the extent of oscillation of the element to control the advance of the toothed member.

9. In a knitting machine, rotary means including a toothed member, an oscillatory element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, so that during an oscillation of the element in one direction the lever first moves therewith to cause its tooth to mesh with said toothed member and then moves angularly relatively thereto to impart an advancing movement to said toothed member, and so that during an oscillation of the element in the reverse direction the lever first moves therewith to disengage the tooth from the toothed member and then engages said stop to be retarded thereby to establish a definite angular relationship between the lever and element at the end of movement of the element, means for varying the extent of oscillation of the element to control the advance of the toothed member, and means rotating with the toothed member for controlling the last named means.

10. In a knitting machine, rotary means including a toothed member, an oscillatory element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, so that during an oscillation of the element in one direction the lever first moves therewith to cause its tooth to mesh with said toothed member and then moves angularly relatively thereto to impart an advancing movement to said toothed member, and so that during an oscillation of the element in the reverse direction the lever first moves therewith to disengage the tooth from the toothed member and then engages said stop to be retarded thereby to establish a definite angular relationship between the lever and element at the end of movement of the element, and means including an element rotating with the toothed member for

interrupting oscillatory motions of the first mentioned element.

11. In a knitting machine, rotary means including a toothed member, an oscillatory element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, so that during an oscillation of the element in one direction the lever first moves therewith to cause its tooth to mesh with said toothed member and then moves angularly relatively thereto to impart an advancing movement to said toothed member, and so that during an oscillation of the element in the reverse direction the lever first moves therewith to disengage the tooth from the toothed member and then engages said stop to be retarded thereby to establish a definite angular relationship between the lever and element at the end of movement of the element, means for varying the extent of oscillation of the element to control the advance of the toothed member, means rotating with the toothed member for controlling the last named means, and means for overriding the last mentioned controlling action to effect uniform advancing movements of the toothed member.

12. In a knitting machine, rotary means including a toothed member, an oscillatory element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, so that during an oscillation of the element in one direction the lever first moves therewith to cause its tooth to mesh with said toothed member and then moves angularly relatively thereto to impart an advancing movement to said toothed member, and so that during an oscillation of the element in the reverse direction the lever first moves therewith to disengage the tooth from the toothed member and then engages said stop to be retarded thereby to establish a definite angular relationship between the lever and element at the end of movement of the element, means for varying the extent of oscillation of the element to effect single or double advances of the toothed member upon each complete oscillation of the element, and means for overriding the last mentioned means to insure only single advances of the toothed member.

13. In a knitting machine, rotary means including a toothed member, an oscillatory element having at least one tooth engageable with said toothed member to impart step by step advancing movements thereto and to prevent overrun thereof, means for varying the extent of oscillation of the element to control the extent of advance of the toothed member, and means rotating with the toothed member for controlling the last named means.

14. In a knitting machine, rotary means including a toothed member, an oscillatory element having at least one tooth engageable with said toothed member to impart step by step advancing movements thereto, means for imparting oscillatory movements to said element, and means for interrupting such oscillatory movements, said element, during periods of interruption of its

movements, being located to lock said toothed member against movement in both directions by engagement of said tooth between teeth of said toothed member.

15. In a knitting machine, rotary means including a toothed member, an oscillatory element having at least one tooth engageable with said toothed member to impart step by step advancing movements thereto, means for imparting oscillatory movements to said element, means for varying the extent of oscillation of the element to control the advance of the toothed member, and means for interrupting such oscillatory movements, said element, during periods of interruption of its movements, being located to lock said toothed member against movement.

16. In a knitting machine, rotary means including a toothed member, an oscillatory element having at least one tooth engageable with said toothed member to impart step by step advancing movements thereto and to prevent overrun thereof, means for varying the extent of oscillation of the element to control the extent of advance of the toothed member, means rotating with the toothed member for controlling the last named means, and means for overruling the last mentioned controlling action to effect uniform advancing movements of the toothed member.

17. In a knitting machine, rotary means including a toothed member, a first lever, means for imparting oscillatory motions to said lever, a second lever having at least one tooth engageable with teeth of the toothed member, the second lever being pivoted to the first lever but being restrained from free angular movement relative thereto, a stop engageable by the second lever to limit movement thereof away from the toothed member, and stop means for limiting angular movement of the second lever relative to the first in one direction, so that during an oscillation of the first lever in one direction the second lever first moves therewith to cause its tooth to mesh with said toothed member and then moves angularly relatively thereto to a position limited by said stop means to impart an advancing movement to said toothed member, and so that during an oscillation of the first lever in the reverse direction the second lever first moves therewith to disengage the tooth from the toothed member without imparting a rotating force to said toothed member and then engages said stop to be retarded thereby to establish a definite angular

relationship between the levers at the end of the movement of the first lever.

18. In a knitting machine, rotary means including a toothed member, an oscillatory element, means for imparting oscillatory motions to said element, a lever having at least one tooth engageable with teeth of the toothed member, the lever being pivoted to said element but being restrained from free angular movement relative thereto, a stop engageable by the lever to limit movement thereof away from the toothed member, and stop means for limiting angular movement of the lever relative to the element in one direction, so that during an oscillation of the element in one direction the lever first moves therewith to cause its tooth to mesh with said toothed member and then moves angularly relatively thereto to a position limited by said stop means to impart an advancing movement to said toothed member, and so that during an oscillation of the element in the reverse direction the lever first moves therewith to disengage the tooth from the toothed member without imparting a rotating force to said toothed member and then engages said stop to be retarded thereby to establish a definite angular relationship between the lever and element at the end of movement of the element.

19. In a knitting machine, rotary means including a toothed member, an oscillatory element, means for imparting oscillatory motions to said element, a lever having at least one tooth engageable with teeth of the toothed member, the lever being pivoted to said element but being restrained from free angular movement relative thereto, and a stop engageable by the lever to limit movement thereof away from the toothed member, so that during an oscillation of the element in one direction the lever first moves therewith to cause its tooth to mesh with said toothed member and then moves angularly relatively thereto to impart an advancing movement to said toothed member, and so that during an oscillation of the element in the reverse direction the lever first moves therewith to disengage the tooth from the toothed member without imparting a rotating force to said toothed member and then engages said stop to be retarded thereby to establish a definite angular relationship between the lever and element at the end of movement of the element.

ROBERT H. LAWSON.
